UNITED STATES PATENT OFFICE.

WEBSTER ROBERTS, OF CLEVELAND, OHIO.

SHAFT-HANGER.

SPECIFICATION forming part of Letters Patent No. 326,789, dated September 22, 1885.

Application filed May 4, 1885. (No model.)

To all whom it may concern:

Be it known that I, WEBSTER ROBERTS, of Cleveland, Cuyahoga county, and State of Ohio, have invented a certain new and Improved Shafting-Hanger, the nature of which relates to such a construction and arrangement that when it is suspended in position for receiving the shafting the journal-box of the hanger can be accurately adjusted to the axial line of the shafting without changing the entire hanger for that purpose. Said adjustment is made by simply moving the journal-box of the hanger to adapt it to the line of shafting. Hence the journal-box or the bearing for the shaft, instead of an integral part of the hanger, is a distinct section adjustably secured in the hanger for the purpose specified. That the construction of the hanger may be fully understood, reference will be made to the accompanying drawings, making part of the following specification.

Figure 1 represents a view of the hanger taken endwise the shafting. Fig. 2 is a view of the hanger shown lengthwise the line of shafting. One arm of the hanger is shown as broken away that the journal-box may be fully seen. Fig. 3 is a sectional view taken through the line $x-x$, Fig. 1. Figs. 4 and 5 are detached sections, and will be referred to in description.

Like letters denote like parts in the drawings, in which A and B represent the arms of the hanger, by which it is suspended. Midway between the two arms is secured a socket, C, by means of the webs D, which also reinforce the suspending-arms by connecting them to each other, as seen in Fig. 1. In the lower end of the socket C is inserted a movable core, E, the lower end of which is provided with a pair of ears, a a, Figs. 1 and 2. The space between the two ears is in the arc of a circle, having its center in the axial line of the set-screw b. Said arc of a circle is adapted to the curve of the block F, projecting upward from the top of the cap G of the journal-box. The said block is an integral part of the cap, as seen in Fig. 3. The curve of the face of the block is described from the center of the arc before mentioned—viz., the set-screw b, alluded to. I is a set-screw for securing the core E in the socket, which is vertically adjusted therein by the adjusting-screws J for a purpose presently shown. The lower part of the hanger

consists of the U-shaped section K, Fig. 1, provided with ears c c, adapted to the ears d d of the hanger, the upper section thereof above described, and to which the lower section is secured by the bolts L. Forming an integral part of the lower section of the hanger is a socket, M, like the socket C, above described, and has therein a core, N, similar to the core E, and arranged in alignment therewith, as seen in the drawings. The upper end of the core N terminates in a pair of arms, e e, Figs. 1 and 2, between which depends from the lower section, H, of the journal-box a projection, O, Figs. 2 and 3. It will be observed in Figs. 1 and 2 that the upper ends of the arms e e, alluded to, describe the arc of a circle, and are adapted to fit, respectively, in corresponding arcs of a circle in the bosses m m, formed on the sides of the section H of the journal-box. Upon said arms e e the box is supported in the hanger, and in view of its curvilinear connection with the arms the journal-box can be vibrated thereon, and which may be made fast in its connection therewith by the adjusting-screws h h', which pass unthreaded through the arms and are screwed into the projection, as seen in Fig. 5. The core N is made fast in its socket by the set-screw b, and is upwardly supported upon screw Q, as seen in Fig. 3. At the under side of each end of the journal-box is an oil-receptacle, a' a', open to the inside of the box by oilways b' b', respectively, which are openings made through the plate c', covering the said oil-receptacles, and forming portions of the inner surface of the box and a supporting-surface for the Bab-bitt-metal lining d'.

Fig. 4 represents an inside view of the lower half of the journal-box without having therein the lining, it being removed that the surface of the plate c' may be seen, and an open view of one of the oil-receptacles a', above mentioned, its plate having been removed for that purpose. On the top of the journal-box are oil-cups A'; also, there are oilways in the side of the box, as seen at P P, by which oil is conducted into the oil-receptacles a' a'. Oil is conducted from the receptacles to the journals by capillary attraction. For that purpose is inserted in the holes b' b' any suitable fibrous material.

Practically the operation of the above-described hanger is as follows: It is necessary in

putting up a line of shafting that every journal-box and bearing of the shaft should be in exact alignment one with the other, that the journals may run without binding in their respective boxes, and thereby avoid heating and undue wearing of the journals and their seats. As hangers are usually made this is a matter of much trouble, to avoid which is the object of the herein-described hanger; and when it is suspended in the usual way by the arms A and B, and in close proximity to the line required for the shafting, the journal-boxes are then adjusted in exact alignment as follows: In the event a journal-box is found to be too low for the shaft-line it can be raised upward exactly to the line of shafting by the supporting-screw Q, acting on the end of the case N, then fastened by the screw b. Should the journal-box be too high for the shaft-line, it can be readily and easily lowered by backing out the screw Q so far as is necessary to lower the core N far enough to bring the box in exact position to the shaft-line. The core is then secured in the socket by the set-screw b, and the box held down firmly in place by the core E, in the upper section of the hanger, being forced down upon the box by the adjusting-screw J.

From the above it will be seen that the journal-box can be easily and readily raised or lowered in the hanger, as the nature of the case may require, to adjust the box in exact relation to the line of shafting. If the axial line of the journal-box is not horizontal or in line with the shaft, as it should be, the box can be readily adjusted to that position by loosening of the screws h h' and then slackening the core E in its socket. The journal-box may then be rocked or moved on the arms e e in either direction to bring it to a horizontal position or in such position as the axial line of the shafting may require. The box when thus adjusted is made fast by screwing down the core E, thereby clamping the journal-box between the arms e e and the end of the core E, which will hold it firmly in position from any vertical and rocking movement. A third adjustment of the journal-box is made in a lateral direction, in order to bring its axial line coincidently with that of the shaft-line. To this end the pressure of the core E upon the journal-box is released, and one of the screws h in the arms e e screwed outward. Then on screwing the other screw h' inward it will draw the journal-box laterally, or in the direction of the arrow seen in Fig. 5, to adjust the box to the line of shafting, which is done in the most exact manner. In this position it is secured by turning in the screw h hard against the opposing screw h', thereby clamping the part O between the two screws h h'. It will be obvious that the latter adjustment of the journal-box may be made either to the right or to the left, as the nature of the case may demand.

65 The several described adjustments of the journal-box are made after the hanger or hang-

ers have been put in position approximating an exact one, the close and final adjustment being done as and by the means and in the manner before shown and described.

70

What I claim as my improvement, and desire to secure by Letters Patent, is—

1. In a shafting-hanger, the socket C, having movably fitted therein a core, E, provided with a curved lower end, adjusting-screw J, and set screw, in combination with a journal-box from the cap of which projects upward a block, the edge thereof being adapted to fit to and vibrate in the curve in the end of the core between the ears thereof, and transversely free to move between said ears, substantially as described, and for the purpose set forth.

75

2. In a shafting-hanger, the lower section, K, thereof provided with a socket, M, set-screws b, and adjusting-screw Q, and having movably fitted therein a core from the upper end of which projects a pair of arms, e e, having curved ends adapted to fit the arc of a circle in the bosses m m of the lower section of the journal-box, and upon which arms the box is supported and vibrates, and adapted to move laterally upon the said arms, operated for that purpose by adjusting-screws h h', and by which the box is secured, substantially as 90 described, and for the purpose specified.

85

3. In a shafting-hanger, the lower section, H, of the journal having its axis of vibration at h h', below the axial line of the journal-bearing, in combination with the upper section of 100 the box, having the arc of its vibration described from the axial center h h', and coinciding with the arc of the arms e e, substantially as set forth, and for the purpose described.

95

4. In combination with the shafting-hanger, 105 a journal-box having the lower section thereof provided with oil-receptacles a a', supplied with oil through the ways P P, plate or cover c c', having therein oilways b b', and said oilways P P, substantially as set forth, and for 110 the purpose specified.

100

5. A hanger for shafting consisting of the suspending-arms A B, socket C, having therein a movable core, the outer end of which is the arc of circle adapted to fit the curve of the 115 block F of the upper section of the journal-box, in combination with the lower section of the journal-box provided with bosses m m, having therein formed the arc of a circle coinciding with the curve of the arms e e of the core N, 120 and on which arms the journal is supported, vibrates, and is laterally adjustable, adjusting-screws h h' and Q, in connection with set-screw b, constructed and arranged substantially as described, and for the purpose set 125 forth.

115

In testimony whereof I affix my signature in presence of two witnesses.
